MEANS FOR AND METHOD OF FORMING
GRINDING WHEELS

Walter F. Ross, Northville, Mich., assignor, by
mesne assignments, to Niles-Bement-Pond
Company, West Hartford, Conn., a corporation
of New Jersey

Application February 8, 1946, Serial No. 646,253

2 Claims. (Cl. 125—11)

1

This invention relates to means for and method of forming or dressing the periphery of an abrasive wheel, such as may be intended for the cutting of gear teeth, wherein the periphery of the said abrasive wheel is to be provided with a thread form in which the threads and the spacing between the threads are to be of a definitely predetermined contour in cross-section calculated to produce well-formed and properly spaced teeth in the work eventually produced by the said abrasive wheel.

More particularly, the invention relates to the profiling of the periphery of an abrasive wheel by the crusher roller method in which a suitably hard abrasive-resisting roller having annular ribs thereon of a rack section, in counterpart of the cross-section of the thread to be formed on the wheel, is pressed against and reciprocated laterally across the periphery of the wheel in timed relation to the rotation of the wheel so that it will roll the thread form thereinto.

This method of crushing a thread form into the periphery of a grinding wheel is not broadly new, and the present invention relates more particularly to the provision of a more efficient form of crusher roll for the more effective purpose of producing a threaded form on an abrasive wheel.

As hitherto proposed, the crusher roll has been of a cylindrical form in which the diameter of the annular rack teeth or ribs has been maintained equal throughout the length of the roll and in which the profile of each of the said ribs has been identical, so that, if such a cylindrical cutter be disposed at an angle to the plane of the abrasive wheel, that is, with its axis at an angle to the axis of the said abrasive wheel in order that the planes of the annular ribs will agree with the lead angle of the thread to be formed on the abrasive wheel, contact will be initially established between the crusher roller and a single point of rotation on the periphery of the abrasive wheel, the outer ribs being out of contact therewith.

Furthermore, such a cylindrical crusher roll has a characteristic crushing action which is exerted more especially on the tops of the grains comprising the grinding wheel, in a manner which leaves an undesirable surface of broken instead of dislodged grains on the formed thread and a surface structure of the thread which is undesirable in many respects for precision grinding of gear teeth or for similar purposes.

Still further, the use of such a form of crusher roll fails to afford such full and complete support for the thread structure of the abrasive

2

wheel during its formation as to effectively minimize breakdown of the said structure or its distortion from the precise, continuous profile desired.

5 The present invention, therefore, has as an important object the provision of a crusher roll which will have a resultant component of crushing and tangential forces when in operation, and in which a rotary slipping action between the crusher roll and the wheel periphery will be provided for to create the tangential force and to effect a dislodging of grains from the structure of the thread as it is formed on the grinding wheel, thereby minimizing the mere breaking of the 10 grains and resulting in the production of a highly abrasive surface on the formed thread structure.

Still further, objects or advantages, auxiliary or subsidiary to the aforesaid objects, or resulting 15 from the construction or operation of the invention as it may be carried into effect, will become apparent as the said invention is hereinafter further disclosed.

In carrying the said invention into effect, I 20 may provide a crusher roller having a substantially hourglass form operated in the manner and by the mechanism hereinafter further described, by way of example having reference to the accompanying drawing wherein:

25 Figure 1 is a somewhat schematic elevation of a mechanism for the profiling of an abrasive gear grinding wheel by means of the improved crusher roll, the precise proportions of the elements of the structure as shown being departed from or exaggerated for purposes of clear and simple illustration.

30 Figure 2 is a schematic plan view of some of the parts shown in Fig. 1.

35 Figure 3 is a front elevation of the crusher wheel together with the finishing wheel and the mountings therefore.

40 Figure 4 is a detailed vertical sectional view of the mountings of the crusher and finishing wheels illustrating their method of adjustment.

45 Figure 5 is a diagram illustrating in an exaggerated manner, the relationship of the crusher wheel to the abrasive wheel being operated on thereby as viewed along the axis of the abrasive wheel; and

50 Figure 6 is a similar diagram showing the abrasive wheel and the crusher wheel as viewed perpendicularly to the axes thereof.

Similar characters of reference indicate similar parts in the several figures of the drawings.

55 Referring first to Figure 1 of the drawings; 10

indicates an abrasive wheel, such as may be intended for the grinding or forming of teeth on a spur wheel blank, the said abrasive wheel being characterized by its having formed on its periphery a thread 11 which is in cross-section conjugate to the rack form of the gear to be ground; and the present invention relates to the means of forming this thread on the periphery of the abrasive wheel.

For such purposes I utilize an annularly ribbed crushing roll 12 having a rib to rib spacing, which is equivalent to the circular pitch of the gear which the abrasive wheel is eventually intended to grind, and this roll is of a special slightly hour-glass form as and for the purposes which will be further described.

I have also provided a further finishing roll 13, which is shown as being of a single channel dual-ribbed construction and is the substantial duplicate of the central portion of the crusher roll 12 embracing the two innermost ribs of the said crusher roll as will become still more apparent as the purposes and operation of these two rolls 12 and 13 are later dwelt upon.

The abrasive wheel 10 and the crusher roll 12 are intended to have relatively reciprocal motion imparted thereto, and, in the present example, such reciprocation is confined to the abrasive wheel although as a matter of design it could be imparted to the crusher roll to produce the same result as will be well understood; and it is desired that throughout the present description and in interpreting the claims that the utilization of the terms "reciprocating the abrasive wheel" be considered in such broad sense as to embrace the obvious alternative of the reciprocation of the pressure roller relative to the abrasive wheel.

The abrasive wheel 10 is shown as being mounted for rotation on and by the shaft 14 which is splined, as at 15, for longitudinal sliding connection with a driving coupling 16, the latter being in turn driven by the bevel gear 17 of a differential which includes pinions 18 and a further meshing bevel gear 19.

20 is a driving motor operating a driving pinion 21 which meshes with ring gear 22 of the said differential, this ring gear also meshing with the first of a train of change speed gears 23, 24, 25, 26 and 27. The said gear 27 drives a feed screw 28 which is threaded into the arm 29 of a bracket 30 secured to the said shaft 14. This bracket 30 is provided with suitably adjustable stops 31 and 32 positioned for the timed operation of a reversing switch 33 for effecting the reversing of the drive motor 20 as said switch is operated by one or another of said stops.

34 is a shaft through which rotation of the gear 19 of the differential may be effected from any suitable source, as by a belt 35, to control the speed of rotation of the shaft 14 relative to that of the driving motor to meet special circumstances; but this is not an essential part of the present invention and need not be discussed in any further detail herein.

It will be apparent that by means of the gearing described and the operation of the feed screw 28 thereby, the abrasive wheel 10 may be caused to reciprocate, say, to the extent indicated by the dotted lines in Figure 1, whilst it is at the same time being rotated, and that, as this reciprocation is reversed by the operation of the reversing switch 33 in the apparent manner, the direction of rotation of the abrasive wheel will at the same time be reversed; so that any sta-

tionary point presented to the surface of the grinding wheel during such operation thereof will traverse a helical path thereon and retrace the same path in the opposite direction upon reversal of the motions described.

It has been heretofore suggested in the prior art that a thread could be so formed on such an abrasive wheel, utilizing the motion described, by pressing thereon a cylinder crushing roller capable of angular adjustment relative to the rotational axis of the grinding wheel to agree with the lead angle of the thread to be formed, said roller having identical annular ribs of cross-sectional rack form; but it has also been recognized that such a roller has a non-uniform normal contact with the periphery of the abrasive wheel so that tangential oscillation or sliding movement of the cylindrical crusher roller across the face of the wheel has been resorted to for the purpose of insuring that the medial portion of the crusher roller (which is the only portion of such a roller having normal contact with the periphery of the abrasive wheel) may be caused to traverse the whole width of the wheel face to produce the required crushing of the thread form thereinto. Thus the medial portion of the said crushing roll has been charged with the greater part of the work of forming the thread on the said abrasive wheel. The use of such a cylindrical wheel has other rolling characteristics, in its relation to the surface of the abrasive wheel which detract from its efficiency and which will also be further referred to hereinafter.

A very important and advantageous feature of the present invention resides in the utilizing of a freely rotatable crusher roll which departs from the usual cylindrical form in that it is of greater diameter at the ends than in the medial portion thereof, the longitudinal contour of the said crusher roll being characterized by its being curved inwardly from the ends similar to an hour-glass.

An examination of Figures 5 and 6 of the drawings will readily show this hour-glass envelope form of the crushing wheel and its relationship to the abrasive wheel 10, the curved lines 36 indicating the envelope of the working surface of the said crusher roller the ends 37 of which are obviously of greater diameter than is the medial portion of the roller. a—b indicates the axis of the abrasive wheel and x—y the axis of the crushing roller set at an angle which is at right angles to the lead angle c—d of the thread to be formed on the periphery of said abrasive wheel. It will be obvious that with this envelope of the correct curvature the outer edges of all the ribs provided on such a crushing roller will simultaneously contact the surface of the abrasive wheel 10 along the line x—y; and it will be also apparent that those ribs so contacting the surface of the grinding wheel, and spaced outwardly from the medial portion of the roller as exemplified by the intersection of the lines a—b and x—y, will be of progressively increasing diameter notwithstanding the fact that the diameter of the abrasive wheel 10 remains constant at such points of contact.

Consequently, the free rolling of the crusher roller on the surface of the abrasive wheel, as the said abrasive wheel is rotated, cannot be a true rolling action for all of the contacting ribs and at best can only be a compromise between the true rolling action of those ribs of smallest diameter and those of largest diameter; and this is a condition highly desirable and sought for

in the present case. It should be understood that the depth and form of the grooves of the crusher roll are located from this curved or hour-glass surface and not from the axis of the roller, as has been the practice heretofore.

The hour-glass crusher roller described, in contra-distinction to the cylindrical pressure roller heretofore known, has a resultant component of a crushing force and tangential force in action. While the peripheral speed of the crusher roller along its actual rolling diameter is uniform, a slippage occurs at diameters other than the rolling circle, due to the hour-glass shape of the roll, creating tangential force which, in forming the thread on the abrasive wheel, is found to break fewer grains whilst dislodging a great quantity of grains; the result being an extremely improved abrasive surface condition on the finally threaded abrasive wheel. On the contrary, the old type cylindrical roller has a single high compressive force in one direction toward the axis of the abrasive wheel which crushes and breaks the tops of the grains in such a manner as to leave an undesirable working face of broken grains.

In the crusher roller as illustrated it will be understood that, with the symmetrical form of crusher roller shown, the point of intersection between the lines *a*—*b* and *x*—*y* falls midway between the ends of the roller for which reason this portion of the roller of smallest diameter is herein referred to as the "medial portion" for the sake of identification; but it is not intended that such definition shall be so narrowly interpreted as to exclude the positioning of this portion of smallest diameter at other than precisely midway between the ends of the roller as it will be perfectly obvious that the said roller will still operate in the manner described should one or other of the end portions of the roller be cut off so that the waist of the roller would no longer be midway of the ends thereof.

It will also be understood that in addition to the free rolling action of the crusher roller, the said abrasive wheel (in the particular example illustrated) is moved backwards and forwards along its axis *a*—*b* as by the mechanism already described, the direction of rotation of the said abrasive wheel being reversed with each movement, as stated, so that the rolling direction of the crusher roll is also reversed at such times.

Means are provided for supporting the crusher roller in operative position relative to the abrasive wheel with provision for its angular setting and fitting into the surface of the abrasive wheel as the operation of forming the thread is carried out and Figures 3 and 4 show a suitable fixture for this purpose.

In its preferred form, the curved hour-glass shape of the crusher roller conforms precisely with the curvature resulting from the intersection of the plane of the setting angle of the crusher roller with the peripheral surface of the abrasive wheel (which is the angle at which the roller is to be set in order that its ribs will truly follow the lead angle of the thread to be formed on the abrasive wheel), so that an even crushing pressure on all contacting ribs on the crusher roller with the said peripheral surface of the abrasive wheel may be maintained throughout all relative reciprocal and rotary motions of the roller and the wheel; but it is within the purview of this invention that the true hour-glass curvature referred to may be departed from within reasonable limits without material

loss of the component of crushing force and tangential force resulting from differences in diameter of the several annular ribs, as hereinbefore explained.

5 A suitable fixture for mounting the crusher roller for adjustment and operation is shown in some detail in Figures 3 and 4; 38 being a frame structure bolted to the bed 39 of the machine and carrying a slide 40 adjustable by micrometer feed 41 toward and from an axis of abrasive wheel 10. The front end of the said slide carries a bracket 42 in which the spindle 43 of the crusher roller 12 is suitably mounted, this bracket being pivoted at 44 for swinging about an axis passing transversely through the axes of the crusher roller 12 and the abrasive wheel 10. It is preferred that this pin be located opposite the medial portion or the waist of the hour-glass crusher roller with its axis directed between adjacent annular ribs of the said crusher roller as clearly seen from an examination of the said Figures 3 and 4.

45 are locking screws for securing the said bracket 42 in position of angular adjustment about the axis of the said pin 44. The purpose of 25 this angular adjustment is to secure the required setting angle of the crusher roller 12 relative to the axis of the abrasive wheel 10 as dictated by the lead angle of the thread to be crushed into the peripheral surface of the said abrasive wheel.

30 Also mounted on the top of the said slide 40, and adjustable thereon by the micrometer feed 46, is a supplementary slide 47 carrying the bracket 48, which in turn is pivoted at 49. This bracket 48 is inverted in relation to the previously described crusher roller bracket 42 and similarly carries the spindle 50 of the finishing or straddle roller 13. The pivot 49 of this bracket 48 is similarly positioned so that its axis is projected through the axes of the said straddle roller 13 40 and of the abrasive wheel 10 and bears the same disposition to the ribs of the roller as does the pivot 44 to the adjacent ribs of the crusher roller 12.

In their truly vertical positions of adjustment, 45 the axes of the spindles 43 and 50 are in alignment, but it will be seen that when the crusher roller is adjusted to an angular setting, as shown in Figure 3, the finishing or straddle roller 13 50 may be adjusted to a like angle of setting and locked in such position of setting by the locking screws 51.

Regardless of the setting angle determined upon and effected by the adjustable means described, it will be observed that those portions of 55 the two rollers intersected by the axes of the pivots 44 and 49 remain stationary, one above the other so that by so arranging the limits of axial feed of the abrasive wheel 10 it may be caused to move from its engagement by the crusher roller 12 to engagement by the finishing of straddle roller 13 which will then have the same relationship to the thread formed on the abrasive wheel by the crusher roller as had the crusher roller itself.

65 The proper spacing of the straddle roller from the crusher roller to insure this may be accomplished by adjustment of the vertical micrometer feed 52 provided for that purpose. It will be understood that this vertical feed 52 may serve 70 to retract the finishing or straddle wheel vertically to a position where it is quite clear of the abrasive wheel 10 during the operation of forming the thread thereon by the action of the crusher roller 12.

75 This finishing or straddle roller, being relative-

ly short and involving only two ribs, does not call for any correction for hour-glass shape as such would be infinitesimal and impractical, and its purpose is to provide a finishing or final forming pressure for the thread in a manner applied to both sides thereof such as to avoid any tendency, during such finishing, to break away the thread by simple unsupported side pressure, especially as such thread approaches the extremities of the abrasive wheel, the crusher having by that time accomplished the greater portion of the thread forming work.

What I claim is:

1. In a machine for crusher rolling a helical thread on the peripheral surface of a cylindrical abrasive wheel composed of abrasive particles bonded in a crushable bond, in combination, driving means operatively connected to said abrasive wheel for rotating said wheel, an annularly ribbed, freely rotatable crusher roller of substantially hourglass shape and having a surface characterized by a plurality of annular, V-shaped grooves, said crusher roller being of non-abrasive material and being of sufficient hardness to crush-form the peripheral surface of said abrasive wheel, means operatively connected to said crusher roller for supporting said roller for free rotation and for holding and pressing said roller against and into the periphery of said abrasive wheel during rotation thereof, whereby said crusher roller and abrasive wheel rotate at substantially the same peripheral velocity, means operatively connected to said support and holding means for pivotally adjusting said support and holding means about a transverse axis radial to said wheel to adjust the axis of said roller at right angles to the thread to be formed on said wheel, and means operatively connected to said crusher wheel for effecting traversing motion between said wheel and said roller during rotation of said wheel, whereby the ribs of said roller will traverse the thread to be formed on said wheel.

5 2. A method of crusher rolling a helical thread on the peripheral surface of a cylindrical abrasive wheel composed of abrasive particles bonded in a crushable bond which comprises mounting said wheel adjacent an annularly ribbed, freely rotatable crusher roller having a surface of substantially hourglass shape with the axis of the wheel positioned in a plane parallel to the axis of the roller and at an acute angle thereto, said crusher roller being of non-abrasive material and being of sufficient hardness to crush-form the peripheral surface of said abrasive wheel, rotating said wheel while holding and pressing the said roller against and into the periphery of said wheel and simultaneously traversing said wheel across said roller, whereby said crusher roller and abrasive wheel rotate at substantially the same peripheral velocity and the ribs of said roller traverse the helical threads being crush rolled on said wheel.
